Emery, Varney, Blair & Wright

UNITED STATES PATENT OFFICE.

ANSON J. BENTLEY, OF NILES, OHIO.

FREEZING CAN.

Application filed December 27, 1920. Serial No. 433,164.

To all whom it may concern:

Be it known that I, ANSON J. BENTLEY, a citizen of the United States, and a resident of the city of Niles, county of Trumbull, and State of Ohio, have invented an Improvement in Freezing Cans, of which the following is a specification.

The present invention relates to improvements in freezing cans used in the manufacture of ice and particularly to an improved construction of can wherein means are provided to force air into the can at or near the bottom to agitate the water which is to be frozen; this being the commonly accepted practice in what is known as the raw water can system of ice making.

In the manufacture of ice by the so-called raw water system it is customary to provide freezing cans which are immersed in a freezing solution such as brine. In order that the impurities commonly present in water available for the manufacture of ice may not be frozen into the finished cakes of ice, some means are provided for introducing air into the can of water at or near the bottom. The action of this air current upon the water is such that the impurities are not frozen into the ice, but are collected in the small amount of water which remains unfrozen in a pocket in the ice cake at the termination of the freezing period.

Many different constructions have been suggested and used by which the air may be introduced into the water. Generally a pipe or tube of some sort is provided which is attached to the outside, or sometimes to the inside of the can, and opens into the can somewhere near the bottom and has its other end readily accessible for connection with a source of compressed air. The most generally used process of manufacturing ice requires that the freezing cans, which are adapted to contain three hundred or more pounds of water, be handled several times for every cake of ice produced. For example, the can must first be placed in the brine solution, filled with water either before or after being placed in the tank and when freezing has been completed, taken from the brine by a traveling crane, immersed in warm water to loosen the ice cake and inverted to dump the ice cake out of the can. Several cans are usually handled together. It will be readily seen that in so

much handling the cans are subjected to very rough treatment.

Considerable difficulty has been encountered in protecting the air tube from injury. If it is located externally of the can, it is apt to be jammed or pulled off the can during handling and if it is located internally it is apt to be separated from the can by the action of the water both when it is freezing and when the ice is being removed from the can.

It is an object of the present invention to so construct the can that the air tube will be fully protected as well from external injury as from internal injury.

A preferred embodiment of the invention has been selected for purposes of illustration and description and is shown in the accompanying drawings, wherein—

Figure 1 is a perspective view of a freezing can embodying a preferred form of the invention.

Figure 2 is a similar view with parts of the can cut away,

Figure 3 is an enlarged top plan view of one corner of the can, and

Figure 4 is an enlarged detail perspective view similar to Figure 2.

The freezing can shown in the accompanying drawings may be made in accordance with Letters Patent No. 1,027,802, dated May 28, 1912, in so far as the general construction, its side walls and bottom, and the formation of seams, are concerned. The can shown comprises two pieces of galvanized sheet metal, one of which forms the side wall 1 and the end wall 2, while the other forms the side wall 3 and the end wall 4. A third piece of sheet metal is suitably cut to form the bottom 5 of the can. The side walls may, if desired, be formed with grooves 6 in order to stiffen them.

As before stated, it is desirable to protect the air tube as completely as possible and herein an illustrative construction is shown whereby the tube may be completely protected in a can of the type referred to. This is accomplished without any appreciable increase in the amount of sheet metal used in the formation of the can and without substantially changing the present mode of manufacture, all of which will obviously result in a distinct economy.

In the formation of the sheets which con-

stitute the walls of the can, a lip or protecting flange is rolled up from the normal plane of the sheet adjacent one or both of the seams. In the present instance, the 5 seams come near the corners of the can and consequently the protecting lip 7 is rolled or otherwise formed along the edge of the sheet which forms the side wall 3. Obviously, the corresponding edge of the side 10 wall 1 may be similarly formed if it were desired to place two tubes in the can. This lip 7 may extend the entire length of the side of the can, or may terminate a slight distance above the bottom as shown in Figure 2 and is of such dimension that it will 15 enclose an appropriate air tube.

In the manufacture of freezing cans it is customary to join the two sections forming the side and end walls by riveting. When 20 these two sections are brought together an air tube 8 may be laid in position and when the rivets have been headed over to make the joint, the lip 7 in cooperation with the corner of the side wall 2 will hold the tube 25 8 firmly in the corner of the can. This tube may be of sufficient length to extend slightly beyond the lower end of the lip 7, or terminate on a level with the bottom of the lip as may be desired.

30 When both seams have been formed, the bottom of the can may be put in place and securely riveted. Then a reinforcing band 9 may be placed around the top edge of the can and likewise securely riveted in place. 35 The several joints of the can may now be soldered in the customary manner and the soldering of the seam adjacent the tube will provide additional means for securing the tube firmly in place.

40 The construction just described provides complete protection for the air tube. It is protected on the outside by the corner of the side 2 and on the inside by lip 7 formed from the metal of the side 3. If desired, 45 some form of fitting, appropriate to the particular system in which the can is to be used may be connected with the upper end of the air tube.

The invention may be modified and variously embodied within the scope of the 50 subjoined claims.

I claim as my invention:

1. A freezing can for use in the manufacture of ice comprising, in combination, 55 sheet metal side members each constituting the complete side wall of the can for a substantial portion of its periphery, said side members being overlapped and connected along a vertical seam and formed adjacent 60 said seam to present between the inner face of the outer overlapping portion and the outer 65 face of the inner overlapping portion a vertical channel and a tube within said channel arranged to conduct air to a point near the 70 bottom of the can.

2. A freezing can for use in the manufacture of ice comprising, in combination, sheet metal side members each constituting the complete side wall of the can for a substantial portion of its periphery, said side members being overlapped and connected along a vertical seam, the edge portion of one side member beyond the seam being formed to provide a protecting vertical channel and an air tube inserted in said channel for conducting air to a point near the bottom of the can. 75

3. A freezing can for use in the manufacture of ice comprising, in combination, a bottom member, sheet metal side members 80 each secured thereto, the edge portion of one side member overlapping the edge portion of another side member and secured thereto along a vertical line to form a seam, the extreme edge portion of one side member beyond the seam, being bent to provide a tube protecting channel, and a tube within said channel to conduct air to a point near the bottom of the can. 85

4. A freezing can for use in the manufacture of ice comprising, in combination, a bottom member, sheet metal side members each secured to the bottom member along its lower edge and having vertical edge portions overlapping each other to form a seam, the outer side member being secured at its edge to the outer face of the inner side member along a line parallel to and spaced a short distance from its edge, the free edge portion of the inner side member beyond the seam 90 being bent to form between itself and the body of the outer side member a protecting channel communicating along its whole length with the interior of the can and an air tube positioned in said protecting channel and extending toward the bottom of the can. 95

5. A freezing can for use in the manufacture of ice having a lip with a free edge struck up along an edge of one of the metal 100 sheets forming the wall members of the can and an air tube located between said lip and another of said metal sheets adjacent the line of jointure of said sheets.

6. A freezing can for use in the manufacture of ice comprising, in combination, sheet metal side wall members each constituting the complete side wall of the can for a substantial portion of its periphery, a portion 110 of one of the side wall members being distorted to form a vertical protecting channel wherein an integral portion of one of said wall members separates said channel from the exterior of the can, and a tube in said channel for conducting air to a point near the bottom of the can. 115

7. A freezing can for use in the manufacture of ice having a peripheral side wall comprising imperforate sheet metal side wall members, each constituting the com- 120 125 130

plete side wall of the can for a substantial portion of its periphery, a portion of the side wall being formed to provide a protecting channel extending vertically down the side 5 of the can to a point near the bottom thereof, one of said imperforate sheet metal side wall members forming the outer wall of said channel and separating it from the exterior

of the can and a tube in said channel to deliver air to a point near the bottom of the 10 can.

In testimony whereof, I have signed my name to this specification this 17th day of December, 1920.

ANSON J. BENTLEY.
